[57]

ABSTRACT

An apparatus for use in the production of spiral-welded tubes or pipes, which comprises a triple roller bending system of a forming body including an outer guide roller device and an inner guide roller device. A first row of rollers is at least individually supported on a beam hydraulically adjustable in a substantially vertical direction on hydraulic cylinders. The adjustment of the displacement stroke of each of the cylinders is effected in such manner that a triple roller bending system is set in accordance with a previously determined relationship between oil pressure and displacement stroke.

1 Claim, 2 Drawing Figures

Fig.1

APPARATUS FOR USE IN THE PRODUCTION OF SPIRAL-WELDED TUBES OR PIPES

The present invention concerns apparatus for use in the production of helically welded tubes in which the displacement or stroke of the bending tool can be manually or automatically adjusted in operation so that even with very different properties of material, various tubes (pipes) can be produced without strain or tension or with a desired amount of tension.

Forming tools for the production of spiral-welded tubes having an outer and inner guide are already known and comprise a triple roller bending system and guide rollers which are arranged either in the form of an outer cage or inner star. Forming bodies are already known in which the triple roller bending system is adjusted in dependence upon the contact pressure, measured by means of pressure boxes between shaped (deformed) sheet metal and guide rollers behind the triple roller bending system so that the said contact pressure and, consequently, the amount of springing up of the pipes is as low as possible. The disadvantage of this arrangement is that the pressure measurement as a value indicator of the displacement of the triple roller bending system is too inaccurate and, in addition, depending on the position of the pressure measuring boxes, for example on the welding gap control of the machine, can be influenced so that the measured pressure is not a measure of the contact ratios of the deformed sheet metal to the guide rollers. Corresponding adjustment of the triple roller bending system would lead to incorrect results.

The present invention however, relates to a forming body, the triple roller bending system of which is controlled to produce spiral tubes without tension (or with desired tension), which system is not pressure dependant, but is rather stroke-dependant. Whilst, in the case of already known arrangements the contact pressure is used behind the triple roller bending system as value indicator and is to be reduced as much as possible by corresponding adjustment of the triple roller bending system — which may lead to incorrect control movements on account of different influences on the pressure measurement, in the present invention the measurement of the difference in the materials and its stroke control are effected in the triple roller bending system itself.

The essential difference between conventional arrangements and that of the present application is therefore that in the first case of the contact pressure subjected to many secondary influences is used behind the triple pressure bending system, and in the second case according to the present invention, a theoretically and/or experimentally predetermined stroke is used in the triple roller bending system as a standard value for the correct positioning of the bending system.

The arrangement of the present invention comprises a triple roller bending system, the front and middle bending beam of which comprising roller supports which are preferably hydraulically adjusted, either jointly or each roller separately in a vertical or inclined direction. This adjustment is effected preferably with stroke-controlled hydraulic cylinders. The stroke of the hydraulic pistons is not controlled in the already known manner so that contact pressure indicator used as a value indicator, is reduced as much as possible behind the triple roller bending system, but in accordance with the present invention, in such manner that the bending

over is adjusted, dependantly on the property of the material, corresponding to a stroke dependance readily and correctly ascertainable experimentally for each type of steel, for producing tubes without tension. If, for example, the strength of the material rises, then the bending moment rises and therewith the action of force from the band on the hydraulic pressure cylinder of the arrangement of the present invention. At the same time the pressure in the closed stroke-controlled system also rises without any initially change in the positioning of the stroke.

The adjustment of the triple roller bending system is not effected in the conventional manner, i.e., purely pressure-dependantly, since the maintenance of a certain pressure on the bending roller and, consequently, also a certain bending moment, still fail to guarantee a uniform springing up amount e.g. almost zero, or makes possible the maintenance of any desired springing amount.

As well known, the band material for shaping the tube is plastically bent-over and when the strain or flow limit of the material is reached during the plastic bending-over, the necessary bending moment no longer rises or only rises so slightly that this change in the bending moment can no-longer be measured reliably in a pipe-forming machine.

The amount of springing-up (or in) of a pipe is determined, exactly as in the bending over of the band material so that the bending over diameter necessary for the springing up measurement zero or for any other desired springing up measurement is maintained. The latter bending over-diameter depends, however, on the fluctuations of the thickness of the material, which are relatively slight, and on the fluctuations in the strength of the material, which are relatively large and which is measured by the force on the rollers of the bending system just as the fluctuations in the thickness of the material are measured. With variations in this force, the bending system must therefore be adjusted and it must be again pointed out that the force does not change with such an adjustment.

In accordance with the present invention, the triple roller bending system is therefore positioned either by vertical or slightly inclined adjustment of the front bending beam alone or with an oppositely directed movement of the middle bending beam together so that a change of stroke corresponds to the rise in pressure in the closed stroke-controlled system with the increase in the strength of the material, said change of stroke being obtained experimentally and/or theoretically for each material quality so that pipes without tension are produced or pipes with a desired amount of springing up or tension are produced. Accordingly, the same applies to positioning in a reduction of the material strength. The preferred hydraulic adjustment of the bending beam or beams of the individual roller cylinder or cylinders can be effected manually or automatically by corresponding positions of the control valves. For example, a stroke scale found for each quality of steel can be arranged around the pressure gauge said scale associating the correct position with each change of pressure.

The invention will be described further, by way of example, with reference to the accompanying drawings, in which:

FIG. 1 is a schematic cross-section through a forming arrangement; and

FIG. 2 is a perspective view of a particular embodiment of a support arrangement, of a roller of the bending system.

The present invention utilizes a three roller bending system which is generally formed of a series of rollers, namely: a first row, a second upper row and a third row which are arranged to form desired bending of a band of pipe material.

A guide cage is formed by rows of rollers 4 which rows are adjusted initially for a desired diameter of finished pipe and preferably remain unchanged in operation.

Similarly, a row of rollers 3 associated with the triple roller bending system is adjusted for the desired finished pipe diameter and preferably remain unchanged in operation.

In contrast to this, row of rollers 2 is adjustable in operation so that they bend incoming band 5 to a diameter which is less than the desired finished diameter. In the embodiment shown, the adjustment of the roller 1 is effected by a hydraulic cylinder 7 which is secured to the machine frame 6 and has a piston rod 8 which carries the roller 1. Each of the rollers is therefore guided and positioned by a cylinder. However, in an alternative arrangement (not shown), all the rollers of the first row may be carried by a common beam and this beam can be hydraulically or mechanically adjusted.

In the embodiment shown, the adjustment indication for the position of the row 1 is effected by a bar 9 which actuates the feeler 10 of a hydraulic copy feeler 11 (e.g. a valve of a servomechanism—see page 407 of Servomechanism Practice, McGraw-Hill, 1960). The copy feeler 11 is mechanically connected to the piston rod 8 by a rod. If, for example, the bar 9 is raised, the feeler 10 is pressed in and permits the flow of oil to raise the piston and, consequently the roller 1. Since the entire copy feeler also rises with the roller 1, the raising of the roller 1 is concluded when the feeler 10 resumes the previous position relative to the bar 9, that is, when the roller 1 has directly copied the adjustment of the bar 9.

It must be emphasised that an electro-hydraulic or electro-mechanical or other adjustment may also be provided, instead of the described direct hydraulic copying.

The fluctuation in the strength of the material and/or the fluctuations in the thickness of the incoming band 5 determine the forces on the rollers 1, 2 and 3. This force is read from the pressure gauge 13 and corresponding pressure gauges may be also provided for the row 2.

For a specific pipe and quality of material reference to the pressure gauge 13 gives an indication of the strength of the material. The correct bending-over diameter associated with the material or the positioning of the rows of rollers 2 and/or 1 is obtained experimentally and/or theoretically and can be given manually or by an automatic indication, for example, by a cam disc acting on the bar 9 or a corresponding member for row 2, which in turn adjusts the rollers 2 and/or 1 accordingly.

After leaving the triple roller bending system that is upon leaving the row of the rollers 3, the tube expands to the (greater) finished diameter or until it comes into contact with the rollers 4. It is always possible to obtain and indicate the bending-over diameter so that the ex-

panded diameter (in which therefore no uncompensated inner strains remain in the pipe wall) is equal to the desired finished pipe diameter. In this case, the springing-up measurement is zero. In practice it may be preferable to leave a small amount of pressure on the rollers 4 to guide the pipe and in order to maintain the finished pipe diameter more simply and accurately. This pressure on the rollers 4 is not directly measured, however, but maintained by a correspondingly corrected positioning of rows 1 and 2.

According to FIG. 1, the triple roller bending system is arranged so that the incoming band runs horizontally or substantially horizontally which results in a simpler machine construction and the bent-over on the roller 15 3 merges tangentially into the finished diameter. Since it is only here that the incoming band runs parallel to the already finished pipe with which it is to be welded, the welding point is just ahead or on the other side of the roller 3. This position of the welding point in the rising band is simultaneously the preferred position for protective gas tack or finished welding. The arrangement shown is therefore preferably provided for so-called "tack-welding" machines.

However, it must be emphasised that the forming system of the present invention is also suitable for submerged arc welding. Since in such welding the welding point must lie in or near the lowest point, the triple roller bending system is turned further forwardly (towards the band inlet). In this case the band must enter at an 25 incline from above or first outwardly over the first roller that is, must be bent oppositely since in each case 30 the sheet metal must be bent over within the triple roller bending system to a diameter which is less than the finished diameter.

FIG. 2 is a part perspective view of an embodiment of the present invention and shows in detail a preferred supporting arrangement of a single roller 1 (or for a roller 2) by respective hydraulic cylinders. The same references are used in FIG. 2 as in FIG. 1 when referring 40 to identical parts.

Furthermore the embodiment of FIG. 2 is supplemented relative to FIG. 1 by footplate 21 by which the unit is connected to the machine frame. Also, a track rod 22 is provided for adjusting all the rollers 1 parallel 45 to the band inlet angle by way of the bolt 23 and the rod 8.

An important feature of FIG. 2 is that the bar 24 (which indicates or dictates the position) is not supported on the machine frame, but has a support (not shown) separate from the frame supporting the triple roller bending system. The advantage of this arrangement is that the elastic deformation of the machine frame originating from the very great bending forces, no longer influences the rated value indication.

Further advantages of the individual supporting arrangement of the roller include that defects in a supporting arrangement no longer have any adverse influence on the machine; and that the roller either presses 55 continuously fully against the band, but is unable to 60 bend it reliably alone or it moves into the other position whilst its load is received by the other rollers. A repair 65 is preferably effected by exchanging a complete unit and for this purpose the band need not be removed from the machine.

Finally it is possible to operate the cylinders and preferably the upper cylinders, hydraulically so that they can deflect pressures toward the hydraulic system upon

the exceeding of a certain pressure. In this manner the (raised) cross welding seam can pass without raising more than one roller and without overloading this or its supporting system or the machine frame.

Another embodiment of the present invention resides in that the band is arranged to run into the bending system horizontally or substantially horizontally and is bent over here to a diameter which is less than the finished diameter so that the entering band is higher than the lower point of the finished pipe. 10

I claim:

1. In an apparatus for the production of helical-welded pipe having guide means defining a circular path for a metal band and welding means for welding each turn as formed to previous turns of the band to 15 form a helical seam pipe, the improvement which comprises:

bending means for imparting a bend to a oncoming band, said bending means comprising a first roller initially encountering said band, a second roller 20 downstream of said first roller and subsequently encountering said band and a third roller down-
